CLAIM

The ornamental design for a module for extra-corporeal heart and/or lung support, substantially as shown and described.

DESCRIPTION

FIG. 1 is a top, front perspective view of a module for extra-corporeal heart and/or lung support comprising a new, original and ornamental design;

FIG. 2 is a rear view of the module for extra-corporeal heart and/or lung support comprising the new, original and ornamental design;

FIG. 3 is a top view of the module for extra-corporeal heart and/or lung support comprising the new, original and ornamental design;

FIG. 4 is a bottom view of the module for extra-corporeal heart and/or lung support comprising the new, original and ornamental design;

FIG. 5 is a top, front, right-hand side perspective view of a module for extra-corporeal heart and/or lung support comprising the new, original and ornamental design;

FIG. 6 is a top, rear, left-hand side perspective view of a module for extra-corporeal heart and/or lung support comprising the new, original and ornamental design; and,

FIG. 7 is a top, rear, left-hand side perspective view of a module for extra-corporeal heart and/or lung support comprising the new, original and ornamental design.

The broken lines are included for the purpose of illustrating portions of the module for extra-corporeal heart and/or lung support that form no part of the claimed design.
